UNITED STATES PATENT OFFICE.

FRANK B. COOK, OF CHICAGO, ILLINOIS.

ELECTROTHERMAL PROTECTOR.

No. 841,849.

Specification of Letters Patent.

Patented Jan. 22, 1907.

Application filed April 16, 1906. Serial No. 311,991.

To all whom it may concern:

Be it known that I, FRANK B. COOK, a citizen of the United States of America, residing at Chicago, in the county of Cook and State of Illinois, have invented a new and useful 5 Electrothermal Protector, of which the following is a specification, reference being had to the accompanying drawings, illustrating same.

My invention relates to electrothermal protectors adapted to protect electrical circuits and apparatus from abnormally large currents of electricity, and especially to protectors adapted to protect from small increments of current above the normal, these currents being generally termed "sneak" currents.

The principal objects of my invention are to provide simplicity of construction in such 20 apparatus, to provide improved means for switching the objectionable current upon the operation of the protector, and to provide means for switching the current either direct or through a portion of the resistance of the 25 heating means.

In the protector of this invention I do not open the main circuit when the apparatus operates, but simply switch the objectionable current to another path, preferably to 30 earth, either direct or through a portion of the resistance of the protector, the apparatus being adjustable to accomplish this end. It is usually customary in protectors of this 35 class to employ a heat-susceptible material, preferably a metallic solder, to secure certain operable portions together or against operation under normal current conditions; this solder generally forming part of the electrical circuit through the protector. In my present 40 invention I do not employ any cementing material whatsoever to hold the device against operation or in the circuit through the protector. I simply separate the switching portion from the protector by heat-susceptible insulating material which softens, 45 due to the heat in the protector under abnormal current conditions, and allows the switching portion to operate and switch the objectionable current to another path.

Referring to the accompanying drawings, illustrating the preferred form of my invention, Figure 1 is a side elevation of the protector of the invention with a portion thereof shown in cross-section. Fig. 2 is a right 55 end elevation of Fig. 1 with one supporting-spring removed. Fig. 3 shows a modified

form of the invention in which the objectionable current is switched from the line direct to ground.

Like characters refer to like parts in the 60 several figures.

Spring members 1, 2, and 3 are preferably mounted on a suitable base or support 4. The heating element 5, preferably a piece of graphite or carbon, is held in place between 65 the free ends of springs 1 and 2, thus completing the main circuit from conductor 6, through spring 1, heating element 5, and spring 2, to conductor 7. Each end of the heating element 5 may be provided with a recess 8, adapted to fit a projection 9 on spring 1 or 2 to firmly hold the element 5 in place against side pressure. The piece of graphite 5 is preferably firmly held in place between springs 1 and 2, due to their tension, so as to 70 make good electrical connection therewith. The graphite 5 may be soldered to springs 1 and 2, if desired, in which case it is preferably metallically plated on its ends, so as to 75 properly solder. In case it is not soldered to 80 springs 1 and 2 it may be readily and easily removed or replaced by another element 5 if damaged in any way.

The spring member 3 is preferably the switching member and is preferably connected to earth at 10. A piece of heat-susceptible insulating material 11 is placed between the free end of spring 3 and the heating element 5, as shown in Fig. 2, so as to normally insulate spring 3 from 5. Spring 90 3 is normally under tension toward the element 5, and this tension securely holds the insulating member 11 in place. If this insulating member is softened or removed, the spring 3 will then come in contact with the 95 element 5, due to its own tension, and thereby make electrical connection therewith.

In Fig. 3 I have provided the heating element 5 with terminal caps 12 and 13, which are preferably soldered to the element 5 in the usual manner. The terminal caps 12 and 13 are preferably engaged with spring members 14 and 15, respectively, in a well-known manner to securely mount the protector in operative position. The switching-spring 16 is arranged near one end of the protector to engage the elongated end cap 13 when the protector is heated, and thereby establish a direct short circuit from conductor 6 to ground at 10. When this protector is used in connection with telephone-switchboard apparatus, conductor 6 is preferably con-

nected to the line and conductor 7 to the switchboard. This order of connection may be reversed, however, if desired, in which case the line coming in at 7 would be switched 5 to ground through the entire resistance of the heating element 5 of the protector.

In Fig. 1 the switching-spring 3 may be adjusted along the length of the heating element 5 so as to connect conductor 6 (or 7) to 10 ground at 10 through any desired portion of the resistance 5.

The operation of the device is as follows: When an abnormally large current of electricity traverses the heat-producing element 5 for a sufficient length of time, depending upon the strength of the current, it produces heat in 5, which heat softens the heat-susceptible material 11. When the material 11 is sufficiently softened, the spring member 3, 20 due to its own tension, presses the material 11 out from between itself and the element 5 and makes direct electrical connection with the element 5, thereby connecting the latter with the earth at 10 and switching the objectionable current from one of the main circuit-springs 1 or 2.

With the arrangement shown in Figs. 1 and 2 the objectionable current is switched to earth through a portion of the resistance of 30 5, which portion can be regulated as desired by adjusting spring 3 along the length of element 5. In Fig. 3, however, if the objectionable current comes over conductor 6 it will be switched direct to earth at 10, the 35 entire resistance of heating element 5 and circuit 7 being shunted out, and thereby protected from the objectionable current. If the objectionable current comes from conductor 7, then it will be switched to earth at 10 through the entire resistance of heating element 5. In either case, as in Figs. 1 and 2, either one or the other of conductors 6 or 7 will be protected from the objectionable current.

45 When the abnormal current is removed from the circuit, the apparatus may be again set for another operation by simply separating spring 3 from the element 5 and placing a new piece of heat-susceptible wax 11 between the two. It will readily be seen that the protector may be operated over and over again as many times as desired, it only requiring a new piece of heat-susceptible material 11 after each operation.

55 I do not wish to limit this invention to the exact details of construction as herein shown or to any particular heat-susceptible material for the portion 11. Many modifications may be made in the construction without departing from the scope of the invention or the principles involved. As a heat-susceptible insulating material 11 beeswax, Japanese wax, shellac, palm-tree wax, stearin, paraffin, resin, or the like may be used with 60 very satisfactory results.

What I claim as my invention, and desire to secure by Letters Patent, is—

1. An electrothermal protector comprising a heating element and having a switching member normally held therefrom by heat-susceptible insulating material and adapted to make electrical connection therewith upon heating. 70

2. An electrothermal protector comprising a heating element permanently held in circuit, means for grounding a portion of the heating element under abnormal current conditions, and heat-susceptible insulating material normally holding the grounding means out of 80 electrical connection with the heating element. 75

3. An electrothermal protector comprising a heating element permanently held in circuit, means for switching a portion of the circuit off through a portion of the heating element, under abnormal current conditions, and heat-susceptible insulating material normally holding the switching means away 85 from the heating element. 90

4. Electrical protective apparatus comprising a pair of spring members, a heat-producing element held between the spring members by the tension thereof, a switching-spring member adapted to engage the heating element under abnormal current conditions, and heat-susceptible insulating material normally holding the switching-spring member out of contact with the heating element. 95

5. Electrical protective apparatus comprising a pair of spring members, a heating element held in place between the spring members, a switching member arranged to make electrical connection with the heating element under abnormal current conditions 100 so as to switch the objectionable current off through any desired portion of the heating element, and heat-susceptible insulating material normally holding the switching member out of electrical connection with the heating element. 105

6. Electrical protective apparatus comprising a pair of conducting members, a heating element permanently soldered in circuit with the conducting members, switching 115 means for making electrical connection with the heating element under abnormal current conditions, and heat-susceptible insulating material normally holding the switching means out of electrical connection with the heating element. 120

7. A heat-producing member normally held in the circuit which it is to protect, means for making electrical connection with the heat-producing member for establishing a circuit from the first-mentioned circuit to ground, and heat-susceptible insulating material normally restraining the circuit-establishing means from establishing the grounded circuit. 130

8. A heat-producing member normally held in the circuit which it is to protect, a normally open circuit from the heat-producing member to earth, adapted to be closed under abnormal current conditions, and heat-susceptible insulating material for normally holding the normally open circuit open and arranged to be effected by the heat-producing member.
9. A pair of spring members suitably mounted and each provided with a projecting point near the free end thereof, a heat-producing element normally held between the said spring members near their free ends, each end of the heating element being provided with a recess adapted to fit the said projecting points, a circuit-controlling spring adapted to make electrical connection with the heating element under abnormal electrical conditions, and heat-susceptible insulating material normally holding the circuit-controlling spring out of contact with the heating element.
10. A pair of metallic supports, one being a spring member and each being provided with a projecting point thereon, a heat-producing member connected in circuit with the
- metallic supports and provided with recesses to accommodate the said points, means for grounding the circuit through a portion of the heating element, and heat-susceptible material normally holding the grounding means out of electrical connection with the heating element.
11. A pair of metallic supports, one being a spring member and each being provided with a projecting point thereon, a heat-producing member connected in circuit with the metallic supports and provided with recesses to accommodate the said points, means for switching a portion of the said circuit to another path through a portion of the heat-producing member under abnormal current conditions, and heat-susceptible material normally holding the switching means from switching the said circuit.

As inventor of the foregoing I hereunto subscribe my name, in the presence of two subscribing witnesses, this 14th day of April, 1906.

FRANK B. COOK.
